UNITED STATES PATENT OFFICE.

FRANK M. ASHLEY, OF NEW YORK, N. Y., ASSIGNOR OF ONE-HALF TO WILLIAM A. ARMSTRONG, OF PHILADELPHIA, PENNSYLVANIA.

GAS-ENGINE.

No. 889,887.

Specification of Letters Patent.

Patented June 9, 1908.

Application filed June 19, 1905. Serial No. 265,845.

To all whom it may concern:

Be it known that I, FRANK M. ASHLEY, a citizen of the United States, and resident of New York city, in the county of New York and State of New York, have invented certain new and useful Improvements in Gas-Engines, of which the following is a specification.

The present invention pertains to gas engines and particularly to that type known as the two cycle engine.

The objects of the invention are to provide an engine of this type that may be operated at a higher speed than those heretofore made and that will not explode the charge of combustible gas before the proper time in its cycle, and in which the air and gas are separately compressed and are not brought into mixture until after they enter the cylinder of the engine.

A further object is to provide an engine which will be more economical in its combustion of fuel, than the usual type of two cycle engines heretofore made.

A further object is to provide a construction with two pistons, wherein both pistons co-act to control both the inlet of air and gas, and the exhaust ports.

A further object is to decrease the time required to charge and discharge the combustion chamber of the engine so that the engine may be operated at a higher speed than heretofore in this type of engine, also to increase the effectiveness of the scavenging charge of air by using a plurality of inlet air ports located apart from each other, and also by the arrangement of the ports to effect a proper mechanical mixture of the fuel gases as they enter the combustion chamber.

Referring to the drawings which form part of this specification and in which similar letters of reference indicate corresponding parts, Figure 1, is a front view of my engine, showing the cranks and crank casing in section. Fig. 2, is a central vertical sectional view of the engine, in a plane at right angles to Fig. 1, and showing the relative position of the pistons when the gas is compressed in the cylinder ready for ignition. Fig. 3, is a cross sectional view taken just below the cylinder head as indicated by the divided lines, (see Fig. 2) and showing the inlet and

outlet ports for the air supply. Fig. 4, is a cross sectional view taken on the lines indicated by X, and Y, in Fig. 2, and showing the valves for controlling the gas and air supply to the cylinder of the engine.

A, indicates the cylinder of the engine; B and B' the pistons therein; C, the piston rod attached to the piston B; D, the cross rod; E and E', the connecting rods which drive the cranks F and F'; G, is the connecting rod which drives the center crank G'; H and H' are the shafts on which the cranks are mounted and H² and H³ are the bearings therefor.

I and I' are the driving wheels; G² and G³ are the disks which are secured to the crank G', and are hollowed out on one side as indicated at G⁴ and G⁵, for purpose of balancing.

J, indicates the crank casing and J' the base plate. The casing J, is secured to the cylinder A, by bolts J², as shown.

On the top of the cylinder A, is a cylinder head A', provided with the stuffing box A², for packing the rod C. Secured to the top of the cylinder head A', is a frame A³, having a bearing A⁴, for the support of the rod C. The rod C, is secured to the cross rod D, at D', and the connecting rods E, and E', are pivotally connected to the rod D, at D² and D³.

C', indicates the air compressing chamber, C², the gas compressing chamber and C³, the combustion chamber.

K, indicates the air inlet check valve, and L the air outlet valve, which communicates with an enlarged chamber M, cast in the cylinder casing, and N, is the air conduit leading therefrom to the ports N' and N², controlled by the manually operated valves N³, and N⁴, respectively, on the spindles of the valve handles N⁵, and N⁶. The gas is controlled in the same manner, the gas entering the chamber C², through the pipe O, and port O', and being then forced by the piston B' through the conduit P, (see dotted lines in Fig. 1) to the ports P' and P², indicated by dotted lines in Fig. 2, and one of which is shown in cross section in Fig. 4. Ports P' and P², are controlled by the manually operable valves P³, and P⁴, which are controlled through the handles P⁵, and P⁶, respectively.

Q, is a pipe and Q' is a valve controlling the same and through which pipe the oil may be withdrawn from the crank case.

R and R', are plates on the ends of the pistons for deflecting the incoming gases, the use and construction of which plates are well known in the art.

5 S, and S', are the exhaust ports from the cylinder through which the exhaust gases pass to the common outlet S².

T, and T', indicate the water jacket spaces. Since the general parts of a gas engine are so 10 well known in the art, I think further detailed description unnecessary.

The operation is as follows: To start the engine, the gas is first admitted to the chamber C², through the port O', and since the air chamber C' is normally full of air under atmospheric pressure, the turning of the wheel I, would force the cranks F, F', and G', to turn in unison whereby the piston B' would over-run the port O', and thereafter trap and 15 compress the gas in the chamber C', and force it to the ports P' and P², through which it enters the cylinder chamber C³, when the pistons travel beyond said ports. The piston B, in its upward movement forces the air from the chamber C' through the valve L, 20 into the chamber M, (which chamber M, thus serves supplementary to the chamber C') and conduit N, to the ports N', and N², so that when the pistons B, and B', pass first the air 25 ports on receding from each other in their first stroke, the air under pressure in the chamber M, and conduit N, flows through the ports N', and N², into the cylinder chamber C³, hereinafter termed the combustion 30 chamber, and striking the plates R, and R', the air is deflected in such a manner as to force the air that was previously in the combustion chamber, out through the exhaust ports S, and S', and as the pistons B, and B', 35 travel past said last named ports, the gas inlet ports P', and P², are opened, and the gas under pressure flows into the combustion chamber C³, and immediately thereafter the 40 pistons B, and B', reverse the direction of their movement and the ports P', and P², are first closed thus cutting off the gas supply 45 and immediately thereafter the air ports N', and N², and the exhaust ports S, and S', are closed, the charge of air and gas being trapped 50 in the combustion chamber C³, and compressed and ignited when the pistons are in the position indicated in the drawings. The 55 burning of the fuel gases, forces the pistons apart until they over-run the exhaust ports S, and S', and the air ports N', and N², when the burned gases exhaust through the 60 exhaust ports S, and S', at practically the same time that the air ports N', and N², are opened, whereby the incoming air acts to force out 65 the burned gases, and immediately thereafter the further movement of the pistons opens the gas ports P', and P², and the gas again flows into the combustion chamber, and is again trapped with the air and compressed and burned as before described. The

relative volumes of air and gas entering the combustion chamber C³, are controlled by the valves N³, N⁴, and P³, and P⁴, respectively, which may be adjusted as desired while the engine is running so that the best 70 results may be obtained.

It will be noted that the engine may be operated by using but one of the exhaust ports, and also by using but one gas inlet port and two air inlet ports, which result may 75 be accomplished by simply closing one of the manually operated globe valves leading to one of the gas inlet ports, or it may be operated by using but one air inlet port in combination with the two gas inlet ports, by 80 closing one of said air controlling valves. The valves N³ and N⁴ and P³ and P⁴ therefore enable me to change the quantity of gas entering the combustion cylinder while the engine is in operation and also the relative 85 quantity of each gas and therefore its mechanical mixture, or if desired, to close off one of said air ports and one of said gas ports which might be desirable under certain conditions.

In engines of very large powers such as generators of 1000 H. P. and upwards, the elimination of mechanically operated valves will be appreciated, and the advantage of provision for governing the speed and fuel 95 mixtures and the provision for expediting the charging of the cylinders with fuel gas in the shortest possible space of time and for discharging the burned gases therefrom will be apparent to all engineers skilled in this art. 100

The engine could be designed to work in a horizontal position, if desired.

Having thus described my invention, I will now point out in the following clauses, what I claim as new and desire to secure by 105 Letters Patent,

1. In a gas engine, comprising a cylinder having two air inlet ports, two gas inlet ports and two exhaust ports, two pistons in said cylinder, each of which controls one of said gas inlet ports, one of said air inlet ports and one of said exhaust ports for the purpose set forth.

2. In a gas engine, a cylinder adapted to contain two pistons and having separate gas and air inlet ports located at points therein about where the pistons will rest at the end of their strokes, and two pistons in said cylinder, each of which travels over a gas and an air inlet port and controls the inlet of fluid to said cylinder, said cylinder having an exhaust port through which the products of combustion may be liberated.

3. In a gas engine, a cylinder adapted to contain two pistons and having separate gas and air inlet ports located at points therein about where the pistons will rest at the end of their strokes, and two pistons in said cylinder each of which travels over a gas and an air inlet port and controls the inlet of fluid to 125

- said cylinder, said cylinder having an exhaust port controlled by one of said pistons.
4. In a gas engine, a cylinder adapted to contain two pistons and having separate gas and air inlet ports located at points therein about where the pistons will rest at the end of their strokes; and two pistons in said cylinder, each of which travels over a gas and an air inlet port and controls the inlet of fluid to said cylinder, said cylinder having two exhaust ports, one of said ports being controlled by one of said pistons and one by the other 5 70
5. In a gas engine, a cylinder adapted to contain two pistons and having separate gas and air inlet ports located at points therein about where the pistons will rest at the end of their strokes, and two pistons in said cylinder, each of which travels over a gas and an air inlet port and controls the inlet of fluid to thereto, one of said pistons serving to compress air in one end of said cylinder and one 10 75
- 15 serving to compress gas in the other end thereof, said cylinder having conduits in its wall through which said air and gas may be led to said inlet ports.
6. In a gas engine, a cylinder adapted to contain two pistons and having separate air and gas inlet ports located at points therein about where the pistons will rest at the end of 20 their strokes, and two pistons in said cylinder, each of which travels over a gas and an air inlet port and controls the inlet of fluid thereto, said cylinder having an exhaust port located approximately in line with one of said 25 80
- 30 air inlet ports, one of said pistons serving to compress air in one end of said cylinder and one serving to compress gas in the other end thereof, said cylinder having conduits through which said air and gas may be led to said inlet ports.
7. In a gas engine, a cylinder of uniform internal diameter throughout its length and having two sets of inlet ports each set comprising a gas and an air inlet, and also having two exhaust ports, one of said exhaust ports being located opposite one set of inlet ports and one opposite the other set thereof, two 35 85
- 40 pistons in said cylinder, one of which controls one set of inlet ports and one of said exhaust ports, and the other of which controls the other set of inlet ports and exhaust port, said pistons and cylinder forming a combustion chamber in which portion said ports are located.
8. In a gas engine, a cylinder having an exhaust port and two sets of inlet ports, each set comprising a gas port and an air port, two pistons in said cylinder, a main shaft, means connecting said pistons with said main shaft, a closed crank case forming with one of said 45 90
- 50 pistons a gas chamber in which gas may be compressed by one of said pistons, one end of said cylinder and the other of said pistons forming a chamber in which air may be compressed by said piston, said pistons and cylinder forming a combustion chamber in which ports are located, said cylinder having provision for conducting air and gas to said combustion chamber.
9. In a gas engine, a cylinder having two air inlet ports and a gas inlet port, and two pistons in said cylinder, each of which is connected by suitable transmitting mechanism to a main shaft of said engine and each of which controls one of said air inlet ports. 5 95
10. In a gas engine, a cylinder having two gas inlet ports and an air inlet port, and two pistons in said cylinder, each of which controls one of said gas inlet ports. 10 100
11. In a gas engine, a cylinder having two air inlet ports and a gas inlet port and an exhaust port, and two pistons in said cylinder, each of which controls one of said air inlet ports and one of which controls the exhaust port. 10 105
12. In a gas engine, a cylinder having two gas inlet ports and an air inlet port, and two pistons in said cylinder, each of which controls one of said gas inlet ports and one of which controls said air inlet port, said cylinder having an exhaust port controlled by one of said pistons. 10 110
13. In a gas engine, a cylinder having two air inlet ports and a gas inlet port and two exhaust ports, two pistons in said cylinder, each of which controls one of said air inlet ports and one of which controls a gas inlet port and an exhaust port. 10 115
14. In a gas engine, a cylinder having two air inlet ports and two gas inlet ports and two exhaust ports, a main shaft, two pistons in said cylinder, each of which is provided with means for transmitting its movement to said main shaft, a gas chamber and an air chamber formed by said pistons and said cylinder for the compression of gas and air respectively, a conduit leading from said gas chamber to said gas ports in said cylinder and a conduit leading from said air chamber to said air ports in said cylinder, all of said 10 120
- 15 ports in said cylinder being controlled by said pistons and located in a position to be opened by said pistons immediately before said pistons complete their power strokes substantially as set forth. 10 125
15. In a gas engine, comprising a cylinder having two air inlet ports, two gas inlet ports and two exhaust ports, two pistons in said cylinder, each of which controls one of said gas inlet ports, one of said air inlet ports and one of said exhaust ports for the purpose set forth, and means for restricting the area of said gas and air inlet ports. 10 130
16. In a gas engine, a cylinder adapted to contain two pistons and having separate gas and air inlet ports located at points therein about where the pistons will rest at the end of their strokes, and two pistons in said cylinder each of which travels over a gas and an air inlet port and controls the inlet of fluid to 10 135

said cylinder, said cylinder having an exhaust port through which the products of combustion may be liberated, and means for restricting the area of said gas and air inlet ports.

17. In a gas engine, a cylinder adapted to contain two pistons and having separate gas and air inlet ports located at points therein about where the pistons will rest at the end 10 of their strokes, and two pistons in said cylinder, each of which travels over a gas and an air inlet port and control the inlet of fluid to said cylinder, said cylinder having an exhaust port controlled by one of said pistons, 15 and means for restricting the area of said gas and air inlet ports.

18. In a gas engine, a cylinder adapted to contain two pistons and having separate gas and air inlet ports located at points therein 20 about where the pistons will rest at the end of their strokes, and two pistons in said cylinder each of which travels over a gas and an air inlet port and controls the inlet of fluid to said cylinder, said cylinder having two 25 exhaust ports, one of said ports being controlled by one of said pistons and one by the other, and means for restricting the area of said gas and air inlet ports.

19. In a gas engine, a cylinder adapted to 30 contain two pistons and having separate gas and air inlet ports located at points therein about where the pistons will rest at the end of their strokes, and two pistons in said cylinder, each of which travels over a gas and 35 an air inlet port and controls the inlet of fluid thereto, one of said pistons serving to compress air in one end of said cylinder and one serving to compress gas in the other end thereof, said cylinder having conduits in its 40 wall through which said air and gas may be led to said inlet ports, and means for restricting the area of said gas and air inlet ports.

20. In a gas engine, a cylinder adapted to contain two pistons and having separate air 45 and gas inlet ports located at points therein about where the pistons will rest at the end of their strokes, and two pistons in said cylinder, each of which travels over a gas and an air inlet port and controls the inlet of fluid 50 thereto, said cylinder having an exhaust port located approximately in line with one of said air inlet ports, one of said pistons serving to compress air in one end of said cylinder and one serving to compress gas in the other 55 end thereof, said cylinder having conduits through which said air and gas may be led to said inlet ports, and means for restricting the area of said gas and air inlet ports.

21. In a gas engine, a cylinder of uniform 60 internal diameter throughout its length and having two sets of inlet ports each set comprising a gas and an air inlet, and also having two exhaust ports, one of said exhaust ports being located opposite one set of inlet ports 65 and one opposite the other set thereof, two

pistons in said cylinder, one of which controls one set of inlet ports and one of said exhaust ports, and the other of which controls the other set of inlet ports and exhaust port, said pistons and cylinder forming a combustion 70 chamber in which portion said ports are located, and means for restricting the area of said gas and air inlet ports.

22. In a gas engine, a cylinder having an exhaust port and two sets of inlet ports, each 75 set comprising a gas port and an air port, two pistons in said cylinder, a main shaft, means connecting said pistons with said main shaft, a closed crank case forming with one of said pistons a gas chamber in which gas may be 80 compressed by said piston, one end of said cylinder and the other of said pistons forming a chamber in which air may be compressed by said piston, said pistons and cylinder forming a combustion chamber in 85 which said ports are located, parts forming conduits for conducting air and gas to said combustion chamber, and means for restricting the area of said gas and air inlet ports.

23. In a gas engine, a cylinder having two 90 air inlet ports and a gas inlet port, and two pistons in said cylinder, each of which is connected by suitable transmitting mechanism to a main shaft of said engine and each of 95 which controls one of said air inlet ports, and means for restricting the area of said gas and air inlet ports.

24. In a gas engine, a cylinder having two gas inlet ports and an air inlet port, and two pistons in said cylinder, each of which controls one of said gas inlet ports, and means for restricting the area of said gas and air inlet ports.

25. In a gas engine, a cylinder having two air inlet ports and a gas inlet port and an exhaust port, and two pistons in said cylinder, each of which controls one of said air inlet ports and one of which controls an exhaust port, and means for restricting the area of 105 said gas and air inlet ports.

26. In a gas engine, a cylinder having two gas inlet ports and an air inlet port, and two pistons in said cylinder, each of which controls one of said gas inlet ports and one of which controls said air inlet port, said cylinder having an exhaust port controlled by one of said pistons, and means for restricting the area of said gas and air inlet ports.

27. In a gas engine, a cylinder having two air inlet ports and a gas inlet port and two exhaust ports, two pistons in said cylinder, each of which controls one of said air inlet ports and one of which controls said gas inlet port and said exhaust port, and means for restricting the area of said gas and air inlet ports.

28. In a gas engine, a cylinder having two air inlet ports and two gas inlet ports and two exhaust ports, a main shaft, two pistons in said cylinder, each of which is provided with 130

- means for transmitting its movement to said main shaft, a gas chamber and an air chamber formed by said pistons and said cylinder for compressing gas and air respectively, a 5 conduit leading from said gas chamber to said gas ports in said cylinder and a conduit leading from said air chamber to said air ports in said cylinder, all of said ports in said cylinder being controlled by said pistons and 10 located in a position to be opened by said pistons immediately before said pistons complete their power strokes substantially as set forth, and means for restricting the area of said gas and air inlet ports.
- 15 29. In a gas engine, a cylinder adapted to contain two pistons and having separate gas and air inlet ports located at points therein about where the pistons will rest at the ends of their strokes, two pistons in said cylinder, 20 each of which travels over a gas and an air inlet port and controls the inlet of fluid to said cylinder, and conduits separately delivering gas and air under pressure to said gas and air inlet ports.
- 25 30. In a gas engine, a cylinder adapted to contain two pistons and having separate gas and air inlet ports located at points therein about where the pistons will rest at the ends of their strokes, two pistons in said cylinder, 30 each of which travels over a gas and an air port and controls the inlet of fluid to the cylinder, said cylinder having an exhaust port located approximately in line with one of said air inlet ports, and conduits separately delivering gas and air under pressure to said gas and air inlet ports.
- 35 31. In a gas engine, a cylinder adapted to contain two pistons and having separate gas and air inlet ports located at points therein 40 about where the pistons will rest at the end of their strokes, two pistons in said cylinder, each of which travels over a gas inlet port and an air inlet port and controls the inlet of fluid to said cylinder, one of said pistons 45 serving to compress air in one end of said cylinder, a supplemental chamber for receiving said compressed air, and conduits through which the air from the supplemental chamber and gas under pressure may be led 50 to said inlet ports.
- 55 32. In a gas engine, a cylinder adapted to contain two pistons and having separate gas and air inlet ports located at points therein about where the pistons will rest at the end of their strokes, two pistons in said cylinder, each of which travels over a gas inlet port and an air inlet port and controls the inlet of fluid to said cylinder, one of said pistons 60 serving to compress air in one end of said cylinder, and one piston serving to compress gas in the other end of said cylinder, a supplemental chamber for receiving the compressed air, and conduits through which said air and gas may be led to said inlet ports.
- 65 33. In a gas engine, a cylinder adapted to contain two pistons and having separate air and gas inlet ports located at points therein about where the pistons will rest at the ends of their strokes, two pistons in said cylinder, each of which travels over a gas inlet port 70 and an air inlet port and controls the inlet of fluid to the cylinder, said cylinder having an exhaust port located approximately in line with one of said air inlet ports, one of said pistons serving to compress air in one end of said cylinder, a supplemental chamber for receiving said compressed air, and conduits through which the air from the supplemental chamber and gas under pressure 75 may be led to said inlet ports.
- 80 34. In a gas engine, a cylinder adapted to contain two pistons and having separate air and gas inlet ports located at points therein about where the pistons will rest at the ends of their strokes, two pistons in said cylinder, 85 each of which travels over a gas inlet port and an air inlet port and controls the inlet of fluid to the cylinder, said cylinder having an exhaust port located approximately in line with one of said air inlet ports, one of said pistons serving to compress air in one end of said cylinder, and one piston serving to compress gas in the other end of said cylinder, a supplemental chamber for receiving the compressed air, and conduits through which said 90 air and gas may be led to said inlet ports.
- 95 35. In a gas engine, a cylinder having two gas inlet ports and an air inlet port, two pistons in said cylinder, each of which controls one of said gas inlet ports, and means for varying the admission areas of said gas inlet ports.
- 100 36. In a gas engine, a cylinder having two air inlet ports, a gas inlet port and an exhaust port, two pistons in said cylinder, each of which controls one of said air inlet ports, and one of which controls the exhaust port, and means for varying the admission area of said gas inlet port.
- 105 37. In a gas engine, a cylinder having two gas inlet ports and an air inlet port, two pistons in said cylinder, each of which controls one of said gas inlet ports, and one of which controls said air inlet port, said cylinder having an exhaust port controlled by one of said pistons, and means for varying the admission areas of said gas inlet ports.
- 110 38. In a gas engine, comprising a cylinder having two air inlet ports, two gas inlet ports and two exhaust ports, two pistons in said cylinder, each of which controls one of said gas and air inlet ports and one of said exhaust ports, and means for restricting the areas of said gas inlet ports.
- 115 39. In a gas engine, a cylinder adapted to contain two pistons and having separate gas and air inlet ports located at points therein about where the pistons will rest at the ends of their strokes, two pistons in said cylinder, each of which travels over a gas inlet port 120

and an air inlet port and controls the inlet of fluid to said cylinder, conduits separately delivering gas and air under pressure to said gas and air inlet ports, and means for varying the volume of gas admitted.

40. In a gas engine, a cylinder adapted to contain two pistons and having separate gas and air inlet ports located at points therein about where the piston will rest at the ends 10 of their strokes, two pistons in said cylinder, each of which travels over a gas inlet port and an air inlet port, and controls the inlet of fluid to said cylinder, conduits for separately delivering gas and air under pressure 15 to said gas and air inlet ports, and means for varying the volume of air admitted to the cylinder.

41. In a gas engine, a cylinder adapted to contain two pistons and having separate gas 20 and air inlet ports located at points therein about where the pistons will rest at the end of their strokes, two pistons in said cylinder, each of which travels over a gas inlet port and an air inlet port and controls the inlet 25 of fluid to said cylinder, one of said pistons serving to compress air in one end of said cylinder, a supplemental chamber for receiving said compressed air, conduits through which the air from the supplemental chamber and gas under pressure may be led to said 30 inlet ports, and means for varying the volume of gas admitted to the cylinder.

42. In a gas engine, a cylinder adapted to contain two pistons and having separate gas 35 and air inlet ports located at points therein

about where the pistons will rest at the ends of their strokes, two pistons in said cylinder, each of which travels over a gas inlet port and an air inlet port and controls the inlet of fluid to said cylinder, one of said pistons 40 serving to compress air in one end of said cylinder, and one piston serving to compress gas in the other end of said cylinder, a supplemental chamber for receiving the compressed air, conduits through which air and 45 gas may be led to said inlet ports, and means for varying the volume of gas admitted to the cylinder.

43. In a gas engine, a cylinder, two pistons contributing to form a combustion 50 chamber between them, the construction presenting two gas inlet ports, one of which is located near the end of the stroke of each of said pistons, and an air inlet port and an exhaust port.

44. In a gas engine, a cylinder, two pistons contributing to form a combustion chamber between them, the construction presenting two air inlet ports, one of which is located near the end of the stroke of each of said pistons, and a gas inlet port and an exhaust port.

Signed at New York in the county of New York and State of New York this 13th day of June A. D. 1905.
